UNITED STATES PATENT OFFICE

161,177

CHAIR FRAME

Charles W. Harrison, Warsaw, Ind., assignor to Arnolt Corporation, Warsaw, Ind., a corporation of Indiana

Application September 27, 1948, Serial No. 148,779

Term of patent 14 years

(Cl. D15—8)

To all whom it may concern:

Be it known that I, Charles W. Harrison, a citizen of the United States, residing near Warsaw, in the county of Kosciusko and State of Indiana, have invented a new, original, and ornamental Design for a Chair Frame, of which the following is a specification, reference being made to the accompanying drawings, forming a part hereof.

In the drawings:

Fig. 1 is a front perspective view of a chair frame embodying my new design;

Fig. 2 is another perspective view taken directly from the front and slightly above;

Fig. 3 is a side perspective view; and

Fig. 4 is another side perspective view taken slightly from the front and above.

I claim:

The ornamental design for a chair frame, substantially as shown.

CHARLES W. HARRISON.
